OVERHEAD GARAGE DOOR OPERATOR

Harvey H. Hall, Denver, Colo.

Application August 19, 1948, Serial No. 45,194

6 Claims. (Cl. 268—59)

1

This invention relates to improvements in overhead garage doors. The use of garage doors of the type generally referred to as overhead doors is quite common and is increasing.

There are many different constructions of operating mechanism for such doors, some of which are designed for manual operation and others for operation by means of electric motors.

It is the object of this invention to produce an operating mechanism for overhead garage doors that shall be of extremely simple construction and which can therefore be manufactured without the use of expensive tools.

Another object of the invention is to produce an overhead door mechanism that will not require springs to counterbalance the door.

A further object of the invention is to produce an overhead door operating mechanism of such construction that it does not require tracks along the door frame or underneath the ceiling.

A further object of the invention is to produce a door operating mechanism of such construction that it can be readily applied to any existing doors so that double doors of the usual hinged construction can be used for overhead doors and the change effected at a small cost of labor.

A further object of the invention is to produce a door operating mechanism that is especially adapted for use in connection with an electric motor so that the door may be opened and closed from a distance.

A further object of the invention is to produce a door operating mechanism provided with a locking device that will automatically lock the door when it is brought to closed position and which will also automatically open the lock when the operating mechanism is put into operation for the purpose of opening the door.

The above and any other objects that may become apparent as the description proceeds are attained by means of a construction and an arrangement of parts that will now be described in detail and for this purpose reference will be had to the accompanying drawings in which the invention has been illustrated in its preferred form, and in which:

Figure 1 is a side elevation of a garage door looking from the inside, portions of the garage wall having been indicated by cross hatched lines;

Figure 2 is a section taken on line 2—2, Figure 1, and shows the door in closed position;

Figure 3 is a fragmentary view similar to that shown in Figure 2, but shows the door in open position;

2

Figure 3a is a diagrammatic view of a somewhat smaller scale showing a portion of the door operating mechanism in the position it occupies when the door is fully open;

5 Figure 4 is a section taken on line 4—4, Figure 1;

Figure 5 is a section taken on line 5—5, Figure 1;

10 Figure 6 is a fragmentary side elevation showing the door lock; and

Figure 7 is a plan view of the electrically operated winch employed for opening and closing the door and shows the limit switch mechanism associated therewith.

15 In the drawing reference numeral 10 designates the vertical members of the door frame and reference numeral 11 the lintel. The door frame is surrounded by the walls of the garage which have been indicated by reference numeral

20 12. The door may be of any suitable construction. In the embodiment shown the door has been illustrated as made from tongue and grooved boards 13 positioned in a frame 14. The door is of the proper size to fit the opening and 25 is secured in place by means which will now be described.

Referring now more particularly to Figure 2, it will be seen that a guide member 15 is attached to the door frame by means of bolts 16. This guide may be a flat steel or channel bar or a round bar or even a wooden bar which is spaced from the inner edge of the door frame intermediate its ends, the elongated space between the bar and the door frame has been 30 designated by reference numeral 17 in Figure 2. A link 18 has its upper end connected with bracket 19 by means of a pivot 20. The lower end of link 18 has been shown as provided with an elongated opening 21 which is not always necessary, but which may be present, if desired. Secured to the door near each edge thereof is 35 a bracket 22 having a pivot 23 that extends through the elongated opening 21. Attached to the door at a distance below bracket 22 that is substantially equal to the length of link 18, is a laterally projecting bracket 24 having a spacer, also a trunnion 25 on which is mounted a roller 26. The roller projects beyond the edge of the door and is positioned in space 17 between the guide bar 15 and the outer surface of the door frame.

40 At the lower end of the guide bar 15 where the latter turns inwardly at right angles as shown in Figure 5, there is an adjusting screw 27 that is held in place by means of a lock nut 28. The upper end of screw 27 serves as an

abutment for rollers 26. This screw serves as means for adjusting the door vertically and for aligning it with the door frame. When the door is closed roller 26 rests on the upper end of adjusting screw 27. An eye bolt 29 extends through the door and through the bracket 24, serving to hold the latter in place. A cable 30 has its lower end connected with the eye bolt as shown in Figure 2. It is to be understood that since the mechanisms on opposite edges of the door are alike, only a single one is described.

Referring now to Figure 1, it will be observed that a pulley 31 is connected to the garage wall directly above each vertical edge of the door and that a steel cable 30 passes around each pulley 15 and passes from thence to the winch mechanism 32 that has been shown to a somewhat larger scale in Figure 7. The winch mechanism consists of a shaft 33 mounted for rotation in bearings 34 and 35. This shaft is provided with a worm gear 36 that is operatively engaged by a worm 37 secured to the drive shaft of an electric motor 38. When the motor rotates shaft 33 will be rotated in its bearings. A double drum having three spaced flanges 39 is secured to the shaft. The 20 ends of the two cables are secured each to one drum and therefore when the shaft and drum turn the cables are wound onto or unwound from the drums. When the door is closed and the motor is started, the drums are rotated in such a direction that the cables are wound thereon, thereby lifting the door, which begins to move in an upward direction. The cables are so arranged that when they are first tensioned they produce an inward force tending to tilt the door inwardly. This may be accomplished in many different ways, but in Figure 2, the cables have been shown as passing downwardly between the door and the frame and have their lower ends connected with eye bolts 29 and therefore whenever the cables are tensioned the door will be subjected to a torque, which moves its top inwardly to avoid hitting the lintel. After the door has been tilted sufficiently to pass the lintel, it will move upwardwardly. Rollers 26 guide the door in its upward movement and since the eye of bolt 29 is on the outside of the door while roller 26 is on the inside, a torque force is produced that tends to tilt the door in a counterclockwise direction when viewed as in Figure 2. When the door tilts inwardly, pivot 23 moves inwardly in a corresponding manner and link 18 moves outwardly. When the door reaches a horizontal position like that shown in Figure 3a and in Figure 3 it is held from tilting about pivot 25 by the action of link 18. In Figure 2 link 18 has been shown as provided with an elongated opening 21 for the pivot 23. This is only necessary when the pivot 25 moves to a point above pivot 23. In Figure 3a a construction has been shown in which pivots 23 and 25 are at the same elevation. The link 41, which has been indicated by dotted lines in Figure 3a, merely designates a link joining pivots 23 and 25 and it will be observed that when the construction is such that link 41 is horizontal, the elongated opening 21 is unnecessary. It is, of course, understood that pivot 20 shown in Figure 3 may be at a higher point than that illustrated as the position of this pivot can be varied within wide limits in a vertical direction.

Referring now to Figure 7, it will be observed that the outer end of shaft 33 is threaded and that an elongated nut 42 is secured to the threaded portion. This nut carries two arms 43 and 44 that are connected to the operating lever 45 of a

two-way switch by means of links 46 that have a lost motion connection with the arms. The switch and its operating mechanism is so proportioned and designed that after the motor has turned for a certain length of time in one direction, the switch will operate to stop the motor and to change the connections so that when the current is again established, the motor will turn in the opposite direction. Since the arrangement of limit switches of the two-way type for reversing connections to a motor and the circuit connected therewith, are old and well known in similar apparatus, the circuit connections and the switch construction has not been illustrated as it forms no part of this invention. However, it may be stated here that for controlling the current to the motor, there are at least two switches, one located preferably on the outside of the garage and one on the inside. Such switches are connected in parallel and are operated to open or close the doors as the case may be.

After the door has been opened and is to be returned to closed position, the motor is energized to turn in the opposite direction, thereby allowing the door to unwind the cable from the winch drums. The weight of the door is effective for such unwinding and as it passes downwardly, the upper end thereof is moved outwardly by the action of the link 18.

Attention is called to the great simplicity of the operating mechanism. The guides 15 may be flat pieces of steel bar or round bars as above mentioned. The two guides 15 are identical in size and shape and the same is true with links 18. The brackets 22 are also identical and can be made with a single die, if constructed in that manner. Brackets 24, with their rollers 26 are also of identical construction and are very simple. The hoisting mechanism shown in Figure 7 is also very simple, constituting, as it does, a plate 47 to which the motor 38 is bolted. The two-way switch can be purchased on the open market and this is also true of the worm gear and worm. The winch drums are of very simple construction and can be cast.

It is apparent from the above that this door opening mechanism is of such simple construction and of such design that its manufacture requires practically no special tools and the few parts and the great simplicity of the parts makes it possible to manufacture this door opening mechanism at a comparatively low cost.

Although the door has been shown as controlled by means of a motor, it is, of course, quite obvious that it may be manually opened and closed, in which case means for manual operation is substituted for the motor for the purpose of tensioning the cables to raise the door.

The door is provided with an automatically operable lock which has been shown in Figure 6. This lock consists of a plate 48 having upturned ends 49 that are perforated for the reception of bolt 50. A spring 51 urges the bolt downwardly. A bent lever is pivoted at 51 and has an arm 52 connected with the upper end of the bolt. The part of the lever on the righthand side of the pivot, when viewed as in Figure 6, is forked and angled in the manner shown, the vertex of the angle being at 53. Cable 30 is provided with an enlargement 54 that is larger than the opening between the two fingers of the lever. The cable passes through the bent portion of the lever and when tension is put on the cable to open the door, the enlargement 54 engages the upwardly ranging portion of the lever turning it

in a clockwise direction and raising the bolt to a point above the door. After the door has opened, the enlargement 54 slides over the angle portion of the lever. When the door is closing the enlargement engages the bent portion of the lever from the other side raising the bolt so as to permit the door to close and after the door has closed, the enlargement passes to the other side, permitting the bolt to descend into locking position.

In the above description pulleys 31 have been shown and described as secured to the garage wall. It is obvious that they may be attached to suitable base plates and that the plates may be attached to the upper ends of the guides.

A suitable band brake B may be applied to the motor shaft to bring the motor to a sudden stop when the current is disconnected from it.

What is claimed as new is:

1. An overhead garage door mechanism for use with a door positioned in a door opening having a frame comprising two vertical frame members and a lintel, a vertical guide attached to each vertical frame member, a guide follower on each vertical edge of the door positioned substantially midway between the top and the bottom thereof in longitudinally freely movable engagement with the guide throughout the length thereof, a pulley positioned above the door opening adjacent each vertical edge of the door, a door lifting cable passing over each pulley and downwardly, the lower ends of the cables being attached to the door at a point positioned in outwardly spaced relation to the guide followers, winch means for winding thereon the other ends of the cables to tension them and produce a torque acting to move the upper end of the door inwardly to clear the lintel and the lower end outwardly and thereafter move the door upwardly, and means for controlling the inward tilting movement of the door as it moves upwardly, comprising links pivoted at their upper ends to the door frame, adjacent the lintel, the free ends of the links having a pivotal connection with the door at a point substantially one-half of the distance from the link pivot to the guide followers.

2. An operating mechanism for doors of the overhead type, positioned and in a frame having spaced vertical sides and a lintel, a guide member positioned on the inside of each vertical side frame member, said guides extending from a point near the lintel downwardly to a point substantially half the distance to the bottom of the door, the door having a guide follower on each vertical edge in freely sliding engagement with the guides throughout the length thereof, said followers forming trunnions about which the door may pivot, links pivoted at their upper ends to the door frame, their free ends being pivotally

60

connected with the door at a point positioned above the guide followers a distance substantially equal to the length of the links, cable anchors on the outside of the door substantially at the level of the guide followers, hoisting cables having their lower ends attached to the anchors, pulleys positioned above the door adjacent each vertical edge thereof, said cables passing about the pulleys, and a power operated winch drum positioned on the lintel, the ends of the cables being attached to the drum, whereby when the winch is operated to tension the cables the force applied to the anchors will produce a torque tending to move the upper end of the door inwardly and whereby as the cables are wound upon the winch drum the door will move upwardly pivoting about the guide followers, the extent of inward tilting being controlled by said links.

20 3. A device in accordance with claim 1 in which means is provided for automatically latching the door in closed position after it has been closed and for unlatching the same when the mechanism is put into operation to open the door, said last named means being operated in response to movement of one of the cables and disposed on the lintel for preventing and permitting inward tilting of the upper edge of the door.

30 4. A device in accordance with claim 2 in which a latching device is provided adjacent the upper edge of the door which is operated by movement of the cables in a direction to close the door, for latching the same to the lintel and by movement of the cables in a direction to open the door for releasing said latch.

35 5. A device in accordance with claim 1 wherein the pivotal connection of the free ends of said links includes slots extending longitudinally thereof.

40 6. A device in accordance with claim 2 wherein the pivotal connection of the free ends of said links includes slots extending longitudinally thereof.

HARVEY H. HALL.
